UNITED STATES PATENT OFFICE.

SETH A. RHODES, OF OAK PARK, ILLINOIS, ASSIGNOR TO RHODES-HOCHRIEM MANUFACTURING CO., OF CHICAGO, ILLINOIS, A CORPORATION OF ILLINOIS.

TICKET FOR PRINTING MECHANISMS.

Application filed January 11, 1924. Serial No. 685,495.

To all whom it may concern:

Be it known that I, SETH A. RHODES, a citizen of the United States, residing at Oak Park, Cook County, Illinois, have invented 5 certain new and useful Improvements in Tickets for Printing Mechanisms, of which the following is a specification.

These improvements relate to tickets for such devices as are adapted to print thereon 10 certain data from a wheel having so large a diameter and having the printing characters thereon arranged so close together as necessarily to make an impression of other data than that which is particularly desired to be 15 shown, as in coin-controlled weighing scales adapted to deliver a ticket showing the weight of the person standing on the scale platform. Its chief objects are to provide a ticket according to which the imprinted data 20 is more clearly and definitely set forth, with the avoidance of confusion to the person receiving the ticket, and rendering the data more easily to be read, and to provide a ticket which when normally imprinted by 25 the machine will have a neater and cleaner appearance—a feature of commercial as well as of other importance.

In the accompanying drawings, which form a part of this specification, Figure 1 shows fragmentarily an arrangement of printing devices suitable in a coin-controlled ticket-vending machine; Fig. 2 shows parts illustrated in Fig. 1 at right angles thereto; Fig. 3 is a face view of a ticket showing 30 these improvements, and Figs. 4 and 5 are respective face views of such a ticket in a slightly modified form.

Referring to Fig. 1, the ticket 10 is to be understood as having been fed by suitable 40 mechanism into position to be printed by the printing wheel 11. An inked ribbon 12 is positioned between the ticket or card 10 and the printing characters 13 on the wheel 11. The swinging hammer 14 is adapted to 45 strike upon the ticket and the data shown by the characters 13 is thereby impressed upon the card.

In a ticket-delivering weighing scale the data shown by the impression characters 13

is in the form of numbers indicating pounds, 50 and because of the great variety of weights of persons who may use the scale, say from a few pounds up to 250 pounds, all to be provided for by characters as 13 on the periphery of the wheel 11, the diameter of that 55 wheel must be relatively large to provide the required circumference, and the characters must be placed as close to each other as conveniently may be so that substantially the maximum number of characters may be 60 provided on the periphery of a wheel of minimum diameter. It necessarily results that when the hammer 14 strikes the ticket more of such characters as 13 than the particular ones desired will leave their impressions 65 on the ticket.

I find that it is not essential to a clear reading to indicate all of the weights by numerals, but that it is sufficient if every other pound is so shown, as 172, 174 and 176 70 in Fig. 3, with graduation marks as 15 indicating the intermediate figures. Since several impressions are simultaneously made it is preferable not to show more than every other figure, for the sake of clearness, especially on a card having these improvements for the fewer the numbers shown the less 75 will be the confusion to the recipient of the card, and in this connection consideration must be had of the large number of persons 80 of limited intelligence or small experience in such matters who are constantly using such machines.

Referring to Fig. 3 the card 10, as it is provided in a suitable compartment of the 85 machine for use by it, does not contain either the date 16 or the weight data 17. It does contain, however, the arrow or pointer 18, and it is also printed with two heavy bars 20 in black ink or in some other 90 dark color, for instance purple if the ribbon 12 be purple, or blue if the ribbon 12 be blue. Black will serve, however, for all dark colors of ribbons used. These two dark areas 20 are of such material width as to 95 embrace within their outer limits all of the space on the card which will be printed upon, having reference to the diameter of

the wheel 11, and they define an open space as S between them of a width sufficient to show thereon one complete character as 174, Fig. 3, or about two complete characters as 174 and 176, Fig. 4, and the arrangement is such that the dark areas as 20 render unnoticeable the rest of the characters that would otherwise be displayed on the card. This is due simply to the fact that the imprint upon the dark surfaces as 20 does not provide such a contrast as enables the imprint thereon to stand out.

The only difference between card 10^a, Fig. 4, and that shown in Fig. 3, is that the entire face of the card with the exception of the open space S adapted to receive the impressions is printed in the darker color, a feature shown here to indicate that cards distinctive in appearance may be employed 20 for different operators of such machines; and in Fig. 5 I have illustrated another distinctive card 10^b in which darkened portions 22 are shown only at the places on the card where they are of advantage in limiting the impression to that part thereof desired.

Referring to Fig. 3, the weight of the person indicated is 174 pounds. While the arrow points to that weight, yet if both 172 30 pounds and 176 pounds were clearly shown on that card the indication would not be as clear and certain to the minds of many of the persons who use such machines. With a part of the indicating characters 172 and 35 176 blocked out or cancelled or not shown, the mental impression which the person receiving the ticket has is very definite, for the only number clearly shown is 174.

Referring to Fig. 4 where one character 40 176 is clearly shown and the other character 174 is almost fully shown, it is evident to the person receiving the ticket that the weight is between 174 pounds and 176 pounds. The arrow 18 points to a place near the 45 graduation numbered 15 in Fig. 4, and it can readily therefore be determined that the weight is between 175 and 176 pounds, and that it is about a quarter of a pound more than 175 pounds.

50 For such weights as are expected to be indicated by a coin-controlled machine, such variations as a quarter of a pound are not material, although the weight can be quite accurately determined if desired. The desideratum is that the person who drops a coin into the machine shall receive for that investment a ticket which will indicate at a glance what the weight is, and without confusion. A person receiving the card of Fig. 60 4 will at once know that the weight is approximately 175 pounds. That is ordinarily all he desires to know. If his weight were exactly 175 pounds both the weights 174 and 176 would be fully shown and the 65 arrow would point between them indicating

175 pounds. Such a clear space as that where the imprint occurs, with dark areas on each side thereof, provides means whereby the person may tell at a glance all he wants to know, without much or any reference to 70 the arrow 18.

It is a distinct advantage also that a card be delivered which is neat and attractive in appearance, the same as with any other commodity which one may purchase. Owing 75 to the relatively great diameter of the printing wheel as 11 a card without these improvements would show thereon a number of complete or substantially complete undesirable figures as well as some incomplete ones fading out and being also undesirable. The impression upon the purchaser in such case would be bad and the machine vending such tickets would be less attractive.

The printing wheel 25 provides the dates. An adjustment is made for the date each day that the device is in use. Since the drum or wheel 25 is of relatively small diameter and sufficient space may be provided thereon between the month indications, the 80 blocking-out provisions are not necessary on that part of the card.

Reference should be had to the appended claims to determine the scope of the improvements herein set forth.

I claim:

1. A ticket for use in a ticket-printing, information-vending machine having information data in the form of printing characters arranged side by side and close together on the periphery of a printing wheel of such large diameter as normally to print upon the ticket complete and incomplete character impressions, some of which impressions are not desired to be shown, the ticket having a portion of its surface adapted to receive the desired impressions from the wheel and having immediately adjacent to and on each side of said portion a surface so nearly in conformity with the impressions from the wheel that the impressions adjacent to the desirable ones on the ticket are rendered substantially unnoticeable.

2. A ticket for use in a ticket-printing and vending weighing scale having weight-indicating printing characters arranged side by side and close together on the periphery of a printing wheel of such large diameter as normally to print upon the ticket complete and incomplete character impressions, some of which impressions are not desired to be shown, the ticket having a portion of its surface adapted to receive the desired impressions from the wheel and show them clearly and having immediately adjacent to said portion an area of a color corresponding to such an extent with the color of the impressions made by the printing characters that the printing impressions on said area do not distinctly show.

3. A ticket for use in a ticket-printing vending machine having information data in the form of printing characters arranged on the periphery of a rotating printing member and adapted to print desirable and undesirable character impressions, the ticket having a portion of its surface adapted to receive the desirable impressions from said rotating member and having adjacent to such surface a second surface adapted to render substantially unnoticeable the undesirable impressions.
